UNITED STATES PATENT OFFICE.

HERBERT J. GWYER, OF YONKERS, NEW YORK.

REFRIGERATOR CONSTRUCTION.

Application filed May 22, 1920. Serial No. 383,346.

To all whom it may concern:

Be it known that I, HERBERT J. GWYER, a citizen of the United States of America, residing at Yonkers, New York, have invented 5 a new and useful Refrigerator Construction, of which the following is a specification.

My invention relates to a refrigerator cabinet construction.

It is an object of my invention to provide 10 a cabinet which can be made in "knock-down" parts, which may be easily assembled.

It is a further object of my invention to provide a knock-down refrigerator having but few parts which may be compactly and 15 conveniently stored or shipped.

Other objects and advantages will appear as the specification proceeds.

My invention in its preferred form comprises front and back panel units and a top 20 and a bottom panel unit, and two side panel units for spacing the front and back panel units apart. The top unit and bottom unit are preferably duplicates of each other. The top unit and bottom unit each have a groove 25 therein into which fit corner posts and ends of the side panels. Suitable means such as rods or bolts are provided for securing the top and bottom panel units together to form a rigid cabinet. The cabinet is suitably 30 lined, the lining preferably conforming in shape and size to the various panel units.

In the drawings, which show merely a preferred form of my invention—

Fig. 1 is a perspective view of a refrigerator embodying the principles of my invention.

Fig. 2 is an end sectional view of my refrigerator.

Fig. 3 is a fragmentary plan view of one 40 of the top or bottom units.

Fig. 4 is a fragmentary plan view of the refrigerator with the top removed and one of the side panels being partly broken away.

Fig. 5 is a fragmentary detail perspective 45 view of one of the front corner posts.

Fig. 6 is a fragmentary perspective view of a tie member for securing the front posts together.

Fig. 7 is a fragmentary detail perspective 50 view of one of the back corner posts.

Fig. 8 is a fragmentary sectional view through the top and one side panel.

Fig. 9 is a fragmentary view of one corner of a side panel, part of the lining being 55 broken away.

Fig. 10 is a fragmentary view of the top

portion of one corner showing the means for securing the top and bottom together.

Fig. 11 is a similar view of the bottom corner, and also showing one leg and a roller. 60

Fig. 12 is a plan view of a top or bottom panel unit.

Fig. 13 is an elevation of the front panel unit.

Fig. 14 is a similar view of the back panel 65 unit.

Fig. 15 is a similar view of one of the side panel units.

In said drawings, which show merely my preferred form, 5 designates the top panel 70 unit as a whole. This top panel unit comprises a frame 6 which may be made of bars mitred at the corners and secured together in any suitable manner. The members comprising the frame 6 may be made of the same 75

cross section as the corner posts. The grooves 22 in the frame 6 may be filled with felt to effectively seal the joints between the top and bottom and the co-operating panels. If desired the edge of the frame 6 may be 80 chamfered adjacent the panels to provide a finished appearance. The frame 6 which is similar for both the top and the bottom, may be provided upon the inner side with grooves 7—8 and upon another side with a groove. 85

9. In the grooves 7 and 8 are fitted panel boards 10—11 and between these panel boards there is provided an insulating panel 12. The panel 12 may be made of any suitable insulating material, such as felt, and is 90 preferably spaced from the panel boards 10—11 in order to provide air spaces for insulating purposes. One of the side panel units, to be afterwards described, is fitted in the groove 9 when the cabinet is assembled. 95

It should be noted that the groove 9 is of the same shape all around the top unit and the parts fitting into said groove are therefore preferably of the same thickness.

The bottom panel unit is preferably made 100 as a duplicate of the top unit, except perhaps that the top may have the edges rounded and finished if desired.

The reference character 13 designates the front panel unit as a whole. This unit 105 preferably comprises two corner posts 14—15 which may be secured together by means of the tie beam 16 suitably secured to the tops of the posts. A similar tie beam 16' may likewise be provided to secure the lower 110 ends of the posts together. Between the posts 14 and 15 and likewise secured to the

tie beams is a supporting post 17. The front unit may be provided with apertures for doors and in the illustrative example shown, three doors are provided.

- 5 Each of the front posts, as shown in detail in Fig. 5, has two edges preferably at right angles to each other. In one of the other edges is a relatively wide slot 18 into which the edge of one side panel fits when 10 the cabinet is assembled. In one of the other edges are provided two spaced grooves 19—20, leaving a tongue 21 therebetween. A suitable deep groove or aperture 22 may be provided longitudinally of the posts. A 15 projection 23 projects above the end of the post proper for a reason to be later described. All of the posts are of the same cross section, and the foregoing description of one, will, therefore, suffice for all. On the back 20 post, however, the projection 23' projecting above the end of the post proper, is wider than the projections 23 on the front post.

In assembling the front panel unit, the beam 16 is placed on the top ends of the 25 front posts and is secured thereto as by means of screws passing through holes such as 24, and into holes such as 25 in the posts. The beam 16 is preferably cut out on one side, as shown at 26, and the thickness of the 30 remaining portion 27 is substantially equal to the height of the projection 23. A similar tie beam 16' secures the bottoms of the front posts together. The supporting post 17 is also secured to the ties in any suitable 35 manner, as by means of screws.

A U-shaped or channeled abutment member 28 fits in the grooves 19—20 and over the tongue 21. This abutment projects out a 40 short distance beyond the posts and may act as an abutment for a door. With doors as shown in the drawings, an abutment member such as described will be provided upon each of the front corner posts. The supporting post 17 may also be provided with abutments such as 29 forming abutments for the 45 opposite sides of the doors. These abutments 29 may be formed in any suitable manner, as by means of rabbeting the edge of the post 17.

50 The back panel unit may be made up of the two corner posts and cross-beams as 29' fitting therebetween. The cross-beams 29' are grooved on the ends to fit over the tongues 21 on the corner posts as shown in 55 Fig. 4. The space inclosed by the cross-beams and posts may be provided with panel boards and insulation similar to that described for the top. It may be here noted that in the preferred form the two front 60 posts are rigidly secured together and form a unit with the front and the two back posts are likewise rigidly connected together and form with the panel boards a complete back panel unit.

65 Each side panel unit comprises a frame

such as 30, and each side panel may be provided with panel boards and insulation similar to that hereinbefore described for the top. As shown in Fig. 8, the frame for the side panel unit is rabbeted at both edges 31, 70 and upon one of these rabbeted edges is formed a tongue 32 over which fits a groove in one of the panel boards 33. The other panel board may simply rest against the other rabbeted edge of the frame. A securing device such as 34 shown in Fig. 9 may be provided for securing the mitered ends of the frame together and also holding the panel board in the frame. This securing device is preferably in the form of a disc with 75 downwardly projecting prongs or teeth which may be driven into the frame. The edge 35 projects within the frame and the panel board being passed beneath the edge 35 is firmly held against dislodgment in the 80 frame.

If desired, suitable legs such as 36 may be provided beneath the bottom panel unit. Each leg will preferably have an aperture therethrough, and each top and bottom panel 90 unit will likewise have apertures therethrough in alignment with the deep slot or aperture 22 in each corner post and the aperture in the leg.

Suitable rollers such as 37 may be provided beneath each leg. The roller shown is mounted upon a plate 38 secured to the bottom of the leg. A tie bolt or rod 39 passes down the leg to the bottom end and a nut 40 is secured thereon. The plate 38 100 coming, as it does, in close proximity to the nut, will prevent the latter from backing off from the rod.

When the front unit, back unit, side units and top and bottom units have each been individually assembled, the cabinet may then be assembled. The bottom unit, which is preferably a duplicate of the top unit, is first placed on the floor with the groove, such as 9, on top. The back panel unit may then be placed in one of the grooves in the bottom, the back panel unit and the projections on the end posts all fitting within the groove.

The front panel unit may then be placed in the opposite groove, the projections on the front posts and lower tie member all fitting within the groove. The side panel units may then be slid into the grooves such as 18 in the front and back posts and forced downwardly until the lower ends engage in the groove in the bottom unit. The top unit may then be placed upon the top of the thus far assembled parts. The groove in the underside of the top will then fit over the projections on each of the corner posts as well as over the side panels, back panel beam and front tie member. The rods 39 may then be passed through the apertures in the top member, corner posts, bottom unit and legs (if legs are provided). The upper end of 110 115 120 125 130

the rod 39 may be provided with a head 41 which may conveniently rest upon a corner fastening device such as 42. The nut 40 is next screwed on the lower end of the rod 5 and the top and bottom members drawn toward each other to secure the parts together and form a rigid cabinet.

The inside of the cabinet may, of course, be lined with any suitable material. The 10 lining may be made in sections which conform in shape to the various units. A separate lining strip is preferably provided over the triangular projection on each corner post and each top and bottom frame, in order 15 to give a smooth interior finish.

Between the post 17 and the back panel, I prefer to provide a partition 43 which is preferably spaced from the top and bottom. The supporting shelf for the ice is indicated 20 in Fig. 2 by the reference character 44. The circulation of air in the refrigerator will be downward from the ice shelf, around beneath the partition, and then up and over the top of the partition back to the ice chest.

25 Any suitable pipe such as 45 may be provided for draining the melted ice from the refrigerator.

It will thus be seen that I have provided a "knock-down" refrigerator which may be 30 very readily assembled by unskilled labor. In the preferred form there are only six separate parts of the cabinet to be stored for shipment.

While I have described in great detail a 35 specific and preferred embodiment of my invention, I wish it to be understood that various changes and modifications may be made all falling within the scope of the appended claims.

40 I claim:

1. In a refrigerator construction, four sides, a top unit, a bottom unit, four corner posts, a tie beam across the ends of two of 45 said corner posts and secured thereto for holding the corner posts rigidly together, said top and bottom units fitting over the said sides and the ends of said posts, one of said units having a groove for receiving said tie beam, and rods passing longitudinally 50 of said corner posts and engaging said top and bottom units for drawing the latter together and securing all of said parts together in cabinet formation.

2. In a refrigerator construction, four corner posts, side members between said posts for enclosing the side spaces between the 55 posts, a top unit and a bottom unit each fitting over the ends of said posts and side members, each of said posts having a relatively wide groove in one side for receiving one of said sides, each of said posts having a relatively narrow groove in the bottom of 60 said relatively wide groove, and rods passing through said relatively narrow grooves and engaging said top and bottom units for

drawing the latter together and securing all the parts together in cabinet formation.

3. In a cabinet construction, a back panel unit including corner posts, said posts being of duplicate cross section and each having in 70 one side a relatively shallow wide groove and a relatively deep narrow groove, said posts each having at another side two spaced apart grooves leaving a tongue between them, top and bottom cross beams having 75 projections fixed in said grooves and panels proper fitting in the space between said posts and cross beams, a front panel unit including two posts which are of the same cross section as the back posts, a channeled abutment member fitting over the tongue on one of said front posts and substantially filling that part of the grooves adjacent thereto and forming a jamb for a door, a pair of side panel units fitting in the shallow grooves in said front and back posts for spacing the front and back units apart and a top unit and a bottom unit for engaging said posts, and panel units, for securing the latter together to form a cabinet structure.

4. In a cabinet construction, four corner posts, each post having a relatively shallow groove on one side, two spaced apart grooves on another side and a relatively narrow deep groove extending into each post from one of said sides, panels engaged in some of said grooves for closing the spaces between some of said posts to form a cabinet, a door extending from one of said posts and closing a part of the space between two of said posts, 100 a top member and a bottom member each including a frame fitting over the ends of said posts and a rod extending from the top through said relatively narrow deep groove in each post to the bottom member for securing the parts together to form a cabinet.

5. A structure such as claimed in claim 4, said corner posts and the frame members of said top and bottom members being of substantially duplicate cross section. 110

6. In a device of the character described, a panel member comprising a frame, a panel in said frame, fastening devices for securing said frame together at the corners comprising a flat metal plate having prongs at 115 an angle thereto extending into the frame, said flat plate overlapping the inside of said frame and engaging the side of said panel for holding said panel in place against lateral dislodgment.

7. In a cabinet construction, a back panel unit comprising corner posts and a panel member secured to said posts, a front panel unit, side panel units engaging said front and back panel units, said front panel unit including corner posts and an intermediate post, tie beams securing said corner posts and intermediate post together at the top and bottom, a top having a groove in the under side fitting over said corner posts and 120

one of said tie beams and over said back and side panels for securing the tops of said parts together, a bottom member having a groove therein fitting over said corner posts, said other tie member and back and side panels, for securing the bottoms of said parts together and a rod passing through said posts and securing said top and bottom members together.

10. 8. In a cabinet construction, front, back and side panels, corner posts engaging said panels, top and bottom members having grooves therein into which fit the corner posts and panels, for securing the posts and panels together, rods passing through said top and bottom members and said posts, a nut on each of said rods for drawing the top and bottom members toward each other and plates adapted to support a roller and prevent said nuts from backing off.

9. In a cabinet construction, front, back and side panels, corner posts engaging said panels, top and bottom members having grooves therein into which fit the corner posts and panels, for securing the posts and panels together, rods passing through said top and bottom members and said posts for securing the members together to form a rigid cabinet, each of said panels and top and bottom members including two spaced apart panel boards and a panel of insulating material between said panel boards and spaced therefrom.

10. In a cabinet construction, including four side units, two opposite side units each including two corner posts, cross beams at

the top and bottom of said posts and rigidly secured thereto and forming part of said opposite side units, the second pair of side units each engaging the corner posts of 40 said first mentioned opposite side units, a unitary top member and a unitary bottom member each engaging the corner posts and side units and having interfitting tongue and groove connection with said cross beams 45 at the top and bottom of said posts, one of said side units having a door opening and a door for closing said opening, and rods at the corners extending longitudinally of the corner posts and engaging the 50 top and bottom members for holding the latter to the side units whereby the top, bottom and side units form a rigid cabinet.

11. In a cabinet construction, a back panel unit comprising corner posts and a 55 panel member secured to said posts, a front panel unit, side panel units engaging said front and back panel units, said front panel unit including corner posts and an intermediate post, tie beams securing said front 60 corner posts together at the top and bottom, a top unit and a bottom unit fitting over the ends of said panel units, said top and bottom units having interfitting tongue and groove connections with said tie beams, 65 back and side panel units, and a rod passing through each of said corner posts and engaging said top and bottom units for securing said top and bottom units together whereby all the units will be held together 70 in cabinet formation.

HERBERT J. GWYER.
